GARMENT HANGER

Filed June 29, 1928

Inventor
F. Johnson,

By *Charles A. O'Brien*
Attorney

UNITED STATES PATENT OFFICE

FRED JOHNSON, OF FREEPORT, ILLINOIS

GARMENT HANGER

Application filed June 29, 1928. Serial No. 289,268.

The present invention relates to improvements in garment hangers and has particular reference to that type of coat and trousers hanger constructed from a single length of 5 wire bent to provide a suspension hook, coat and dress shoulder supporting portions, and a transverse reach member from which the trousers may be suspended.

The types of wire garment hanger now 10 generally in use do not provide any means to prevent sliding movement of the trousers from one side of the transverse reach member to the other side and therefore such sliding movement of a pair of trousers results 15 in the trousers becoming wrinkled and often times displaced.

It is therefore one of the principal aims 20 of the present invention to provide a garment hanger wherein a particular transverse reach portion is employed which will eliminate such sliding movement of the trousers on this portion of the hanger and thereby maintaining the trousers in proper condition during the handling of the trousers while suspended 25 from the transverse reach member.

Still a further object is to provide a garment hanger of the above mentioned character which is simple in construction, combination and arrangement of the various elements forming the invention as more fully 30 hereininafter described and claimed, reference being had to the accompanying drawing forming part hereof, wherein like numerals refer to like parts throughout.

35 In the drawing:

The figure represents a front elevation of the garment hanger embodying my invention.

40 In the drawing wherein for the purpose of illustration is shown the preferred embodiment of my invention, the numeral 1 designates generally my improved garment hanger, the same being constructed from a single length of wire, shaped by bending the same into a substantially triangular frame, the ends of the wire being inter-twisted with one terminal extended and shaped to provide a suspension hook 2 above the twisted portion 3.

The shoulder portions 4 are oppositely inclined and may be slightly bent.

The intermediate portion of the length of wire is disposed horizontally and constitutes what I term as the transverse reach portion 5 55 on which the trousers are supported.

The transverse reach portion 5 is of a length materially less than the distance between the lower ends of the shoulder portions 4 and the portions of the wire at the ends of 60 the reach portion 5 are bent back in parallel spaced relation with respect to the end portions of the reach portion 5 to provide what may be termed as a clamping portion 6.

The ends of the clamping portions terminate in the upwardly diverging portions 7 and these diverging portions are arranged approximately forty-five degrees with respect to the clamping portions 6 and the upper ends of the angularly disposed portions 7 terminate in the outwardly and downwardly inclined portions 8, the outer ends of which merge with the lower ends of the shoulder portions 4 as clearly indicated in 75 the drawing. It is to be understood that the wire from which the garment hanger is formed is so bent as to dispose the shoulder portions, reach portions, the trousers clamping portion and the connecting portions between said shoulder portions and the clamping portion in substantially the same vertical plane.

The coat and vest may be supported on the shoulder portions 4 in the usual manner while the trousers are folded over the reach portion 5 and the respective edge portions of the folded portion of the trousers will be clamped between the end portions of the transverse reach portion 5 and the inwardly disposed clamping portions 6 thus maintaining 80 the trousers in position on the hanger against lateral sliding movement so that the trousers cannot become wrinkled or disengaged from the hanger while in transportation.

The simplicity of my improved garment hanger enables the same to be manufactured at a very low cost and may be finished to present a neat appearance.

While I have shown the preferred embod- 100

iment, it is obvious that my invention is susceptible to various changes and modifications in construction without departing from the spirit of the invention or the scope of the 5 appended claim, and I accordingly claim all such forms of the device to which I am entitled.

Having thus described my invention, what I claim as new is:

10 A garment hanger consisting of a single length of wire bent into a substantially co-angular shaped frame, the ends of the wire being inter-twisted and bent to form a suspension hook, shoulder portions extending 15 downwardly in diverging relation from the twisted portions, the intermediate portion of the length of the wire being disposed horizontally to provide a reach portion, the ends of which terminate inwardly of the lower 20 ends of the shoulder portions, the portions of the wire at the ends of the reach portion being bent back above the reach portion in parallel spaced relation thereto to provide trousers clamping portions, the inner ends of 25 the clamping portions terminating in upwardly diverging portions, the upwardly diverging portions terminating in spaced relation with respect to the intermediate portions of the respective shoulder portions, and 30 in downwardly inclined portions that merge at their outer ends with the lower ends of the shoulder portions, all of the aforesaid portions being disposed in substantially the same vertical clamping plane.

35 In testimony whereof I affix my signature.
FRED JOHNSON.
